UNITED STATES PATENT OFFICE.

MAX GÜNTHER WILHELM KOENIG, OF BERLIN-GRUNEWALD, GERMANY, ASSIGNOR
TO MASCHINENFABRIK KOENIG-WERK G. M. B. H., OF BERLIN-GRUNEWALD, GER-
MANY, A JOINT STOCK COMPANY.

PAPER-FEEDING APPARATUS FOR PRINTING PRESSES, FOLDING MACHINES, AND
THE LIKE.

Application filed April 18, 1925. Serial No. 24,152.

To all whom it may concern:

Be it known that I, MAX GÜNTHER WILHELM KOENIG, a citizen of Germany, residing at Berlin-Grunewald, in the State of 5 Prussia, Germany, have invented certain new and useful Improvements in Paper-Feeding Apparatus for Printing Presses, Folding Machines, and the like; and I do hereby declare the following to be a full, clear, and 10 exact description of the invention, such as will enable others skilled in the art to which it appertains to make and use the same.

My invention relates to improvements in paper feeding apparatus for printing presses, folding machines and the like, and more particularly in apparatus of the type shown for example in the patent of the United States Nr. 538,640, granted April 30, 1895, to Briggs and Philpott, in which a pile or 20 bank of paper placed on an upper supply table is passed around a reversing member such as a drum and on a lower feed table so as to be reversed in position, the sheets located while on the upper or supply table at 25 the top of the pile or bank being at the bottom thereof when the pile is passed on the lower or feed table. The object of the improvements is to provide paper feeding means which are simple in construction and 30 reliable in operation, and with this object in view my invention consists in providing supply and feeding tables which are equipped with means for advancing the same in the direction of the feed of the paper 35 and back again and constructing the same so that the power for advancing the pile of paper is larger during the feeding stroke than during the return stroke, and so that during the feeding stroke the pile or bank 40 takes part in the movement of the tables, while it does not take part in such movement during the return stroke.

For the purpose of explaining the invention several examples embodying the same 45 have been shown in the accompanying drawings, in which the same reference characters have been used in all the views to indicate corresponding parts. In said drawings—

Fig. 1, is an elevation of the feeding apparatus,

Fig. 2, is a plan view of the feeding apparatus with the upper or supply table removed,

Fig. 3, is a sectional elevation taken on the line 3—3 of Fig. 1, 55

Fig. 4, is a plan view of the upper table and the reversing member,

Fig. 5, is a diagrammatical view showing the means controlled by the sheet of paper being advanced for interrupting the rotary 60 movement of the sheet feeding roller,

Fig. 6, is a plan view showing a modification of the upper table,

Fig. 7, is a partial elevation showing the tables and the reversing member of another 65 modification,

Fig. 8, is a top plan view of Fig. 7,

Fig. 9, is an elevation similar to the one shown in Fig. 7 and showing another modification, 70

Fig. 10, is a top plan view of Fig. 9, and

Fig. 11, is a sectional elevation showing a reversing member of modified construction.

In the example shown in Figs. 1-5 my 75 improved paper feeding apparatus is shown as used in connection with a printing press,

Fig. 1 showing only so much of the said press as is necessary for illustrating the co-operation thereof with the paper feeding 80 apparatus. The machine comprises a pair of frame members 1 having an impression cylinder 2 mounted in suitable brackets 83.

In front of the said cylinder a table 4 is mounted on the frame members, which provides a guide for the sheets of paper supplied to the impression cylinder, said sheets being arrested in the proper position by the usual vertically movable registering guides 85

5. For advancing the sheets of paper over the table 4 a rotary feed roller 102 and a roller 101 are provided, the roller 101 being mounted on arms 113 adapted to be rocked 90 downwardly for pressing the sheets of paper into frictional contact with the roller 102.

The frame members 1 provide a support for a main or lower feed table made in several sections 11, 12, 13, and on frame portions 7 and 8 a supply table or upper feed table made in sections 14, 15, 16, is guided. 95

Further, a rotary drum 17, 18, 19 is mounted on the portions 7. As appears more particularly from Fig. 2, the section 11 of the lower table consists of two longitudinal boards secured to a transverse bar 20. In a 100

similar way the section 12 consists of two 105

longitudinal boards secured to a pair of transverse bars 21, and the section 13 consists of three longitudinal boards secured to transverse bars 22. The transverse bar 20 is secured to the frame members 1 so that the table section 11 cannot be shifted in longitudinal direction. At their front and rear ends the boards 11 are supported on rollers 23 provided on a transverse shaft 24 secured to the frame members 1 and on rollers 25 carried by a transverse shaft 26 mounted on arms 27 depending from the members 7. The sections 12 and 13 of the table are likewise supported on the rollers 23 and 25 but they are not secured to the frame 1, so that they are adapted to be reciprocated on the said rollers in longitudinal direction. As is shown in Fig. 4, the sections of the upper table are mounted on the frame members 7 and 8 in a similar way, the boards 14 being fixed to a transverse bar 33 secured to the frame members 8 and supported on rollers 29 and 30 carried by shafts 31 and 32 secured to the frame members 7 and 8 respectively. The boards 15 are fixed to transverse bars 34, and they are longitudinally shiftable on the rollers 29 and 30. The boards 16 are fixed to transverse bars 35, and they are likewise movable on the rollers 29 and 30.

For moving the upper and lower tables the following mechanism is provided: On transverse shafts 36 and 37 levers 38 and 39 are rockingly mounted, which are provided respectively with elongated slots 40, 41 and 42, 43, the slots 40 being engaged by pins 44 secured to a transverse bar 6 fixed to the section 15 of the upper table, the slots 42 by pins 45 secured to the section 16 of the upper table, the slot 41 by pins 46 provided on a transverse bar 6' secured to the section 12 of the lower table, and the slot 43 by pins 47 secured to the section 13 of the lower table. At their bottom ends the levers 38 and 39 located at one side of the machine are jointed to a link 48 connected at 49 to a rod 50 adapted to be reciprocated in longitudinal direction. As shown the rod 50 is jointed to a toothed segment 51 having a rocking support at 52. To a rock shaft 53 mounted in the frame members 8 arms 54 are secured which carry a rotary shaft 56 having feed rollers 55, a pulley 9 and a pinion 57 keyed thereto. The feed rollers 55 are adapted for engagement with the sheets of paper placed on the lower table 11, 12, 13 for advancing the same towards the table 4, rotary movement being imparted to the said rollers by suitable means such as a belt gearing including the pulley 9. Normally the rollers 55 are out of engagement with the paper, but they are adapted to be rocked into engagement therewith by suitable mechanism such for example as a cam 88 performing a complete rotation for each operation of the machine and acting on an arm 58 for rock-

ing the same with the rollers 55 into engagement with the paper, a spring 89 tending to retract the roller 55 away from the sheets of paper.

When rocking the arms 54 downwardly the pinion 57 is thrown into engagement with the toothed segment 51 and the rollers 55 make contact with the sheets of paper. Therefore, when feeding a sheet of paper towards the impression cylinder 2 the toothed segment 51 and the levers 38, 39 connected therewith are moved for shifting the tables 15, 16 and 12, 13, as will be described hereinafter. By means of the mechanism so far described only advancing movement is imparted to the tables, the return movement being imparted thereto by mechanism now to be described.

In suitable bearings of the frame members 1 a shaft 60 is mounted which is adapted to be rotated in the direction of the arrow α from the main driving shaft of the machine, said shaft being once rotated for each operation of the machine. To the shaft two cams 61 and 62 are keyed which are adapted to impart rocking movement to levers 63 and 64 secured to shafts 65 and 66. The said levers are adapted to engage lugs 67 and 68 respectively secured to the sections 13 and 12 of the lower table. The cams 61 and 62 are displaced with relation to each other, and when rotating the shaft 60 the levers 63 and 64 are successively engaged by their respective cams, the lever 63 being first engaged by the cam 61 and thereafter the lever 64 by the cam 62, so that at first the table section 13 having the lug 67 secured thereto and thereafter the table section 12 having the lug 68 secured thereto is returned into initial position, such movement being transmitted through the levers 38 and 39 to the upper table sections 15, 16. To permit such successive movement of the table sections the lever 38 engages in a slot 69 of the link 48, so that at first the lever 39 and thereafter the lever 38 is rocked.

The member on which the pile of sheets is reversed and carried from the upper table to the lower one is mounted on a shaft 75 disposed in the brackets 7. The said member is made in sections 17, 18, 19 corresponding in position to the boards 14, 15, 16 and connected therewith by links 76. Therefore the sections 17 are stationary, while the sections 18 and 19 are rocked by the boards 12 and 13 connected therewith. As appears from Figs. 1 and 2 the sections 17 to 19 may be segmental in form. Arms 77 of the bracket 7 carry curved arms 78 adapted to embrace the pile or bank of paper moving around the drums 17, 18, 19 and holding the same in position on the said drums.

The rocking movement of the rollers 55 by means of the cam 88 and the rotary movement of the cams 61 and 62 are derived

in a positive way from the main driving shaft and they are performed in regular succession. The rotary movement of the rollers 55 is controlled by the sheet of paper being fed from the bank of sheets towards the impression cylinder. Suitable means may be provided for this purpose. To show what may be done, the pulley 106 driving the belt gearing 121 is rotatable on a driving shaft 105, and it is provided with a conical coupling member 104. The coupling member 107 cooperating with the member 104 is non-rotatably mounted on the shaft 105 and it can be slightly shifted by a spring 112 out of coupling engagement with the member 104. It is in the form of an electromagnet the coil 108 of which is electrically connected with a pair of collector rings 109 secured to and insulated from the shaft 105. At the left of the rollers 101 and 102 a pair of contact arms or feelers 110 is provided, which are in position for being separated by the sheet of paper advanced through the rollers 101 and 102. The said contact arms are electrically connected with brushes 111 making contact with the rings 109, and the electric circuit includes a battery 123. While the feelers 110 make contact with each other the coil 108 is energized for attracting the coupling member 104 and coupling the pulley 106 to the shaft 105, and when the circuit is interrupted the spring 112 disconnects the coupling members 104 and 108.

The operation of the feeding apparatus is as follows:

In the position of the parts shown in Fig. 1 the rollers 55 and the pinion 56 have been rocked by the cam 88 away from the bank of sheets and the toothed segment 51 respectively, and the arms 63 and 64 have shifted the table sections operated thereby to the right. Upon further movement of the main driving shaft of the machine the cam 62 moving in the direction of the arrow α releases the arm 64, and thereafter the cam 88 rocks the lever 58 with the rollers 55 into engagement with the uppermost sheet of paper, and it retracts the roller 101 away from the roller 102 by means of a rod 114. The electric circuit including the electromagnet 108 being closed the pulley 106 is coupled with the shaft 105. Therefore the rollers 55 are rotated and advance the uppermost sheet of paper towards the left and into position between the rollers 101 and 102 and the contact arms 110. By the sheet of paper passing between the feelers 110 the electrical circuit is interrupted and the electromagnet 108 deenergized, so that the pulley 106 is disconnected from the shaft 105. Thereafter the cam 88 permits the arm 58 to be rocked downwardly by the spring 89 connected to the arm 54, so that the rollers 55 are retracted away from the sheet of paper, and the roller 101 is rocked downwardly and into

engagement with the roller 102, whereupon the sheet of paper is further advanced by the rollers 101 and 102.

When rocking the arm 54 downwardly in the manner described the pinion 57 is thrown into mesh with the toothed segment 51, which segment is rocked to the left by the rotary movement of the shaft 56 imparted thereto by the belt gearing 121. Therefore the levers 38 and 39 are pulled with their bottom ends to the left so as to impart feeding movement to the lower and upper table sections 12, 13 and 15, 16 connected therewith, the extent of the said movement depending on the time required for the rollers 55 to feed the uppermost sheet of paper into position between the feelers 110. Further, the sections 18 and 19 are rocked in clockwise direction. Thus the pile of paper is advanced towards the impression cylinder 2 and with its uppermost sheet into position for engagement by the wheels 55. After the arms 54 have been rocked upwardly the cam 61 gets into engagement with the lever 63. Therefore the boards 13 and 16 are returned into initial positions, the boards 12 and 15 being for the present at rest. Thus the pile of sheets is held in position by friction on the stationary boards 11, 14 and the boards 12, 15. After the cam 61 has released the lever 63 the cam 62 engages the lever 64 and rocks the same into engagement with the lug 68, so that now only the boards 12 and 15 are moved to the right and left respectively, the pile of paper being held in position by friction on the boards 11, 14 and 13, 16 and by gravity.

It appears therefore that during the forward stroke of the boards 12, 13 and 15, 16 the power advancing the pile of paper is supplied by the gravity of the pile moving on said inclined boards downwardly and by the friction of the pile of paper on the boards 12, 13 and 15, 16, while upon the return stroke of the boards the gravity and the friction of the said pile on one set of boards 12, 15 or 13, 16 counteract the return movement of the pile, so that the power for advancing the pile of paper is larger during the feeding stroke than during the return stroke.

In the example so far described the friction on the stationary boards 11 and 14 counteracts the return movement of the pile of paper. However these stationary boards also counteract the forward stroke of the pile. In some cases it will be advisable to provide only movable boards and to return the groups of the said boards in succession. Fig. 6 shows a modification in which all the boards of the upper and lower tables are movable. The upper table shown in the said figure consists of two sets of boards 115 and 116 adapted to be simultaneously advanced and to be successively returned, the boards 115 being secured to a

pair of transverse bars 134 and the boards 116 being secured to transverse bars 135. The construction of the lower table is similar to that of the upper table. The said 5 upper boards are connected by links 176 with sectional drums 118 and 119. The sets of boards are successively returned into initial position by means similar to those shown in Figs. 1 to 4, Fig. 6 showing only 10 the lateral pins 144, 145.

I have found that the same result may be obtained by constructing the upper and lower tables each in one section performing the advancing and the return stroke, in 15 which case however I incline the said tables at a larger angle, so that the gravity assisting the advancing movement and counter-acting the return movement is sufficient to cause the forward movement of the bank of 20 paper and to prevent return movement thereof when the tables move into initial position. In Figs. 7 and 8 I have shown this modification in a diagrammatical way, the figures showing only the integral tables 80 25 and 81, one rocking lever 82 mounted at 82' and actuated by a link 84 for advancing the tables 80 and 81, and an integral drum 85 connected with the upper table 81 by one or more links 86. Since the tables 80 and 30 81 are returned by one stroke no special returning mechanism is required, the return movement being brought about by the lever 82 or the link 84. To show what may be done a spring 87 is attached to the lever 82 35 which tends to rock the said lever in opposition to the link 84.

In Figs. 9 to 11 I have shown a modification in which the tables are subdivided transversely of the direction of their re- 40 ciprocating movement. Otherwise the construction is similar to the one described with reference to Figs. 1 to 4, the tables comprising stationary boards 211 and 214 secured respectively to longitudinal bars 188 and 189, and two sets of movable boards 212, 215 and 213, 216. The boards 212 and 215 are connected by levers 238 and 238' and a link 240, and the boards 213 and 216 are connected by a lever 239. The levers 238 45 and 239 are connected by a link 248 and a rod 250 with operating mechanism such as has been described with reference to Fig. 1, and the lever 239 and the link 248 are in pin and slot engagement with each other. 50 The return movement of the boards 212, 215 and 213, 216 is brought about in the manner described with reference to Fig. 1, and I have shown in Figs. 8 and 9 only lugs 267 and 268 and parts of the levers 55 263 and 264. The drum for reversing the bank of paper is moved only in the direction for advancing the bank of paper, while it is at rest when the tables or table sections 60 perform their return stroke. As shown the 65 drum is made in sections 90 and 91, the sec-

tions 90 being keyed to a tubular shaft 92 rotatable on a shaft 93 suitably supported in bearings of the machine frame. The sections 91 are rotatably mounted on the tubular shaft 92, and they are fixed in position 70 by arms 94 secured to a transverse rod 95 mounted on the frame. On the shaft 93 an arm 96 is rockingly mounted which carries a pawl 97 engaging in a ratchet wheel 98 keyed to the shaft 92. The arm 96 is connected by a link 99 with one of the boards of the upper table. The pitch of the ratchet teeth formed on the disk 98 is very small, so that a small stroke of the table is sufficient to impart feeding movement to the ratchet 80 disk 98 and the drum sections 90. Upon the forward movement of the tables corresponding feeding movement is imparted to the drum sections 90, while no movement is imparted thereto upon the return stroke of 85 the tables.

While in describing the invention reference has been made to particular examples embodying the same I wish it to be understood that my invention is not limited to the 90 constructions shown in the drawings, and that various changes may be made in the general arrangement of the apparatus and the construction of its parts without departing from the invention.

For example, I do not limit myself to a construction, in which the table supporting the bank of sheets comprises only two sections successively performing their return strokes, nor to a construction, in which the 95 said table sections are returned into initial positions each time after they have been moved in forward direction for advancing the bank of sheets.

I claim:

1. An apparatus for feeding banks of sheets of paper, comprising a pair of bank supporting tables located one above the other and inclined downwardly and in opposite directions, a reversing member disposed between said tables at one of the ends thereof, and means to impart feeding and return movement to said tables in opposite directions.

2. An apparatus for feeding banks of sheets of paper, comprising a pair of bank supporting tables located one above the other and inclined downwardly and in opposite directions, a reversing member disposed between said tables at one of the ends thereof, means to impart feeding and return movement to said tables in opposite directions, and means to impart feeding movement to said reversing member.

3. An apparatus for feeding banks of sheets of paper, comprising a pair of bank supporting tables located one above the other and inclined downwardly and in opposite directions, subsidiary stationary bank supporting members disposed with 125 130

their top faces within the planes of the top faces of said tables, a reversing member disposed between said tables at one of the ends thereof, and means to impart feeding and return movement to said tables in opposite directions.

4. An apparatus for feeding banks of sheets of paper, comprising a pair of bank supporting tables located one above the other and inclined downwardly and in opposite directions, subsidiary stationary bank supporting members disposed with their top faces within the planes of the top faces of said tables, a reversing member disposed between said tables at one of the ends thereof, means to impart feeding and return movement to said tables in opposite directions, means to impart feeding movement to said reversing member, and a stationary reversing member corresponding in form and position to said movable reversing member.

5. An apparatus for feeding banks of sheets of paper, comprising a pair of bank

supporting tables located one above the other and made in sections, a reversing member disposed between said tables at one of the ends thereof, means to impart feeding movement to said tables, and means for successively returning the sections of the tables into initial positions.

6. An apparatus for feeding banks of sheets of paper, comprising a pair of bank supporting tables located one above the other and made in sections, a reversing member disposed between said tables at one of the ends thereof, means to impart feeding movement to said tables, means for successively returning the sections of the tables into initial positions, and subsidiary stationary bank supporting members disposed with their top faces within the planes of said tables.

In testimony whereof I hereunto affix my signature.

MAX GÜNTHER WILHELM KOENIG.
